(57) **CLAIM**

The ornamental design for an easy chair, as shown and described.

DESCRIPTION

FIG. 1 is a front elevational view of an easy chair showing our new design;

FIG. 2 is a top plan view thereof;

FIG. 3 is a bottom plan view thereof;

FIG. 4 is a left side elevational view thereof;

FIG. 5 is a rear elevational view thereof; and,

FIG. 6 is a top front perspective view thereof.

A right side elevational view of the easy chair is a mirror image of the left side view shown in FIG. 4, and therefore omitted.
